Filed Mar. 23, 1972, Ser. No. 237,594

Term of patent 14 years

Int. Cl. D8—05

U.S. Cl. D26—1 P

FIG. 1 is a side elevational view of a torch tip showing my new design, wherein the broken lines are shown for illustrative purposes only.

FIG. 2 is an isometric view of the front and side of the torch tip of FIG. 1.

FIG. 3 is an isometric view of the back and other side of the torch tip of FIG. 1.

FIG. 4 is an isometric view of a modified form of the torch tip shown in FIG. 1, wherein the only difference resides in the blunt end configuration.

I claim:

The ornamental design for a torch tip, as shown and described.
